UNITED STATES PATENT OFFICE.

GEORGE C. WORTHINGTON, OF ELYRIA, OHIO.

BALL-WINDING MACHINE.

SPECIFICATION forming part of Letters Patent No. 740,348, dated September 29, 1903.

Application filed March 25, 1903. Serial No. 149,418. (No model.)

To all whom it may concern:

Be it known that I, GEORGE C. WORTHINGTON, a citizen of the United States, residing at Elyria, in the county of Lorain and State 5 of Ohio, have invented a certain new and useful Improvement in Ball-Winding Machines, of which the following is a full, clear, and exact description, reference being had to the accompanying drawings.

The invention has for its primary object the winding of vulcanized-rubber tape upon a core to make a very resilient ball of substantially spherical form, which may form the core of a golf-ball, the shell being formed of 15 gutta - percha. The mechanism, however, may be used for winding other material than this vulcanized-rubber tape.

The invention consists, fundamentally, of two axially-mounted separable disks having 20 concentrically - grooved faces, mechanism whereby said disks are rotated at different speeds, and means for yieldingly opposing the separation of said disks; and it also consists in the more specific combinations of 25 parts hereinafter described, and definitely pointed out in the claims.

In the drawings, Figure 1 is a front elevation of the mechanism in its preferred form. Fig. 2 is an end view thereof. Fig. 3 is a 30 face view of one of the disks. Fig. 4 is a longitudinal sectional view of said disks; and Fig. 5 is a detached view of one of the sets of gears *e* and *k'* to illustrate their different proportioning from the gears *d* and *k* shown in 35 Fig. 2.

Referring to the parts by letters, *A* and *B* represent two ball-holding disks which are mounted in axial alinement. The proximate faces of these disks are provided with concentric grooves *a* and *b*, in which the ball *C* is held while it is being wound. These disks are yieldingly pressed toward each other, so that as the ball increases in size the disks will separate proportionately, but will nevertheless hold the ball and turn it, as at first. In the specific construction shown these disks are respectively secured to the ends of two rotatable shafts *D* and *E*, which are rotatably mounted in suitable standards *F* and *G*. 45 Each standard is composed of two parts *ff* and *gg*, and the driving wheels or gears *d* and *e*, through which said shafts pass, are

50 prevented from endwise movement by lying between the two parts of these standards, respectively. There is a tongue- and -groove connection between each shaft and its associated driving gear or wheel, so that both must rotate together. The two shafts may, however, be moved longitudinally in the standards *F* and *G*.

Surrounding each shaft is a spring *J*, which thrusts endwise against the associated standard and the disk secured to said shaft. I prefer to make both shafts thus movable endwise instead of one only, because thereby the 55 center of the ball being wound does not move out of what may be called the "winding plane" during the operation of the mechanism.

The gears *d* and *e* mesh with other gears *k k'*, 70 which are secured to the driving-shaft *K*. The relative size of gears associated with the shafts *D* and *E* are different, so that the said shafts, and consequently the disks attached to them, will rotate at different speeds. Thus, 75 as shown, the gears *k* and *d* are the same size, each having twenty-sixth teeth, while the gears *k'* and *e* are in the proportion of twenty-five to twenty-seven, that being their number of teeth, respectively. This proportion of the speeds of the two shafts I have 80 found to work well in practice.

In using the mechanism for the intended purpose the operator separates the disks and places between them a core to which one end 85 of the rubber tape has been secured in some suitable way, as by winding some of the tape upon said core. The machine being set in operation, the operator holds the tape in his hand and applies the necessary tension thereto. As the ball is carried around the axis of the disks by their rotation the tape will be wound upon the core; but because of the difference in the speeds of the two disks the ball will be turned, so as to present different 95 great circles in the winding plane.

Very satisfactory results have been attained with disks having grooves of various forms; but on the whole, however, the best results seem to have been attained with 100 grooves of broad V shape, substantially as shown.

In order to provide effective mechanism for separating the disks so that the finished ball

may be removed or a new core to be wound placed between the disks, the mechanism shown, but not heretofore described, is provided. Two bell-crank levers M and N are 5 pivoted to a suitable support. The upturned end of each is forked for engagement with a grooved collar R, mounted upon the associated shaft between two collars r r', fixed thereon. The other ends of these levers are 10 connected by links P with a foot-lever T, by means of which these bell-crank levers may operate and the shafts D and E caused to move endwise in their bearings.

Having described my invention, I claim—
15 1. In a ball-winding machine, the combination of two disks rotatably mounted in axial alinement, with means yieldingly opposing the separation of said disks, and mechanism for rotating said disks at unequal speeds, for 20 the purpose specified.

2. In a ball-winding machine, the combination of two disks rotatably mounted in axial alinement, and having concentric grooves in their proximate faces, with means yieldingly 25 opposing the separation of said disks, and mechanism for rotating said disks at unequal speeds, for the purpose specified.

3. In a ball-winding machine, the combination of two shafts mounted in axial alinement 30 and capable of moving endwise in their bearings, and disks secured to the proximate ends of said shafts and having concentric grooves in their opposing faces, with mechanism for rotating said shafts at unequal speeds, and 35 springs acting to move said shafts in their bearings in the direction to bring the disks nearer together, for the purpose specified.

4. In a ball-winding machine, the combination of two shafts mounted in axial alinement 40 and capable of moving endwise in their bearings, and disks secured to the proximate ends

of said shafts and having concentric grooves in their opposing faces, with mechanism for rotating said shafts at unequal speeds, springs acting to move said shafts in their bearings 45 in the direction to move the disks nearer together, and mechanism for moving said shafts in their bearings in the opposite direction to separate said disks, for the purpose specified.

5. In a ball-winding machine, the combination of two shafts mounted in axial alinement and capable of moving endwise in their bearings, and disks secured to the proximate ends of said shafts and having concentric grooves in their opposing faces, with mechanism for 50 rotating said shafts at unequal speeds, springs acting to move said shafts in their bearings in the direction to move the disks nearer together, grooved collars secured upon said shafts, and forked levers engaging said collars whereby to move the shafts against the force of said springs, for the purpose specified.

6. In a ball-winding machine, the combination of two shafts rotatably mounted in axial 65 alinement, and disks secured to the proximate ends of said shafts and having concentric grooves in their opposing faces; with springs acting to move said shafts in their bearings to carry the disks nearer together, driving- 70 wheels embracing said shafts and having tongue-and-groove connections therewith, means preventing the longitudinal movement of said driving-wheels, and means for rotating said driving-wheels at unequal speeds, 75 for the purpose specified.

In testimony whereof I hereunto affix my signature in the presence of two witnesses.

GEORGE C. WORTHINGTON.
